UNITED STATES PATENT OFFICE.

HENRY BLUMENBERG, JR., OF DAGGETT, CALIFORNIA.

SULFUR-BURNER.

SPECIFICATION forming part of Letters Patent No. 734,397, dated July 21, 1903.

Application filed August 19, 1902. Serial No. 120,247. (No model.)

To all whom it may concern:

Be it known that I, HENRY BLUMENBERG, Jr., of Daggett, county of San Bernardino, and State of California, have invented certain new and useful Improvements in Sulfur-Burners; and I do hereby declare that the following is a full and clear description thereof.

The present invention relates to sulfur-burners.

10 The object of my improvements is to provide an efficient type of sulfur-burner for the purpose of converting the same into sulfur dioxid with a minimum amount of sublimation resulting therefrom.

15 For this purpose my invention consists in the following construction and combination of parts, the details of which will first be fully described and the features of novelty then set forth and claimed.

20 Figure 1 represents a longitudinal vertical section of a device to which I have applied my improvements. Fig. 2 is a transverse vertical section taken through the line xx of Fig. 1. Fig. 3 is a detail plan view of the burner-door. Fig. 4 is an end elevation. Fig. 5 is a side elevation of the device.

In the drawings, 1 represents a horizontal cylindrical chamber provided with end holes 2 for cleaning the same. Chamber 1 is pro-

30 vided with an axial intake-opening 3 at one end and at the other with an outlet-opening 4, through which the SO_2 is taken for the particular industrial use desired. Along the top of the cylinder 1 is disposed an air-supply pipe 5, connected with the pipe 6', leading to any suitable air-compressor. This pipe 5 is pro-

35 vided with a series of vertical depending branch air-pipes 6, which pass down through packing-boxes in the cylinder and discharge

40 near the bottom of said cylinder. The cylinder is lined with fire-brick 7 or other refractory material. The cylinder is provided with a safety-valve 8 and an air-gage 9.

The sulfur is introduced into the cylinder

45 through the door 10. The cylinder 1 is provided with a frame 11 for supporting and guiding the door 10, whereby the same may be opened and closed quickly. For this purpose the door is pro-

50 vided with a counterweight for lifting the door upon releasing the pressure of the clamp which holds it down.

The vertical air-pipes 6 are connected with the air-pipes 5 through horizontal pipes 12. The cylinder is supported firmly upon the foundation by means of gusset-supports 13. The sulfur dioxid produced by this burner may be used for reducing ores, for paper works, for sewerage disposal, or for any other places where burning sulfur is desired.

55 In Fig. 4 the mechanism is illustrated for operating the quick-opening door. The door 10 is carried by a lever-arm hinged to a strap at one side of the cylinder and the other side is provided with a latch device for holding the door upon its seat and applying pressure thereto for sealing the same. A counterweight 60 is also shown supported by a cord running over pulleys and attached to the lever-arm, the weight of which is sufficient to lift and open the door immediately when the door is unlatched.

65 It is to be understood that while I have shown a cylindrical receptacle, yet the receptacle may be of any suitable shape or size.

70 In Fig. 5 an air-pump is shown for supplying air under pressure to auxiliary pipe 5. It may also supply air under pressure to pipe 3 by being suitably connected thereto or an independent source of supply may be furnished.

75 What I claim as new, and desire to secure by Letters Patent, is—

1. In a sulfur-burner, the combination of a burner-chamber having a main air-supply pipe under pressure and a discharge-opening, with a second independent air-supply pipe under pressure disposed outside the chamber and having branch pipes projecting therein and means for supplying air under pressure to both supply-pipes.

80 2. In a sulfur-burner, the combination of a burner-chamber having a main air-supply pipe under pressure and a discharge-opening, with a second independent air-supply pipe under pressure disposed outside the chamber and having branch pipes projecting therein extending down near the bottom of the burner-chamber and means for supplying air under pressure to both supply-pipes.

85 3. In a sulfur-burner, the combination of a burner-chamber having a main supply-pipe under pressure and a discharge-opening, with a second independent air-supply pipe under

pressure disposed outside the chamber and having branch pipes projecting therein and having a series of branch pipes terminating near the bottom of the burner-chamber and 5 means for supplying air under pressure to both supply-pipes.

4. In a sulfur-burner, the combination of a burner-chamber, main air supply and discharge openings, auxiliary air-supply pipes 10 terminating near the bottom of the cylinder,

a door for supplying sulfur thereto, means for clamping the door, and a counterweight for actuating the door.

In testimony whereof I have affixed my signature in the presence of two witnesses.

HENRY BLUMENBERG, JR.
